Primary Examiner — Michelle E. Wilson*Assistant Examiner* — Clesse Moore, Jr.(74) *Attorney, Agent, or Firm* — Zhihua Han; Wen IP LLC(57) **CLAIM**

I claim the ornamental design for a paddle, as shown and described.

DESCRIPTION

FIG. 1 is a prospective view of the paddle showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 is a partially enlarged view showing the central portion of the paddle, taken from the encircled area in the FIG. 1 drawing view.

The broken lines shown in FIG. 1 illustrate environment that form no part of the claimed design.

1 Claim, 7 Drawing Sheets(56)
